UNITED STATES PATENT OFFICE.

FOSE DE ROCHER, OF CHICAGO, ILLINOIS.

GAME-BOARD.

979,445.

Specification of Letters Patent. Patented Dec. 27, 1910.

Application filed July 2, 1910. Serial No. 570,174.

To all whom it may concern:

Be it known that I, FOSE DE ROCHER, a citizen of the United States of America, and a resident of Chicago, in the county of Cook and State of Illinois, have invented certain new and useful Improvements in Game-Boards, of which the following is a specification.

This invention relates to game boards for playing games representing speed contests such as equestrian, foot or like races, or contests, and in which succeeding casts of a cubical die carrying the spots or numerals one to six on its respective faces, afford the means by which the points in the game are made. And the present improvement has for its object to provide a simple, efficient and attractive arrangement or grouping of indicating means or figures upon the surface 20 of the game board, wherewith the attainment of the points in the game are indicated in a ready manner and with which a material increase in the element of chance is introduced into the game, all as will herein- 25 after more fully appear.

In the accompanying drawings: Figure 1, is a plan view of a game board embodying the present invention. Fig. 2, is a detail perspective view of the casting die and box 30 used in connection with the same.

Similar numerals of reference indicate like parts in both views.

Referring to the drawings, 1 represents the board or chart, preferably of the rectangular form shown, and comprising a sheet of mill-board or the like, which may be suitably creased so as to fold together into a compact shape when not in use, and as usual in the present class of game boards.

2, 3, 4, 5, 6 and 7 represent a series of rows of horses and jockeys, or other usual type runners, arranged in radial and symmetrical relation to a central field or space 8 on the board, as shown. In my preferred grouping as shown in Fig. 1, six rows of horses and jockeys are shown, but the number of rows may be increased or decreased if found desirable without departing from the scope of my invention. Each row of horses and jockeys, or the like, will be numbered from one to six, the numerals having an irregular arrangement with relation to each other and also in relation to the numerals of the next adjacent rows, and in my preferred arrangement of said numerals as illustrated in Fig. 1, will be as follows: The first row com-

mences from the outside with the numeral 6, and follows with the numerals 3, 5, 2, 4 and 1. The second row commences from the outside with the numeral 5, and follows with the numerals 2, 6, 4, 1, and 3. The third row commences from the outside with the numeral 3, and follows with the numerals 1, 4, 5, 2 and 6. The fourth row commences from the outside with the numeral 2, and follows with the numerals 5, 3, 1, 6 and 4. The fifth row commences from the outside with the numeral 4, and follows with the numerals 6, 1, 3, 5 and 2. The sixth row commences from the outside with the numeral 1, and follows with the numerals 4, 2, 6, 3 and 5. 9 is an ordinary cubical die, and 10 the box from which the same is cast usually upon the central field or space 8 aforesaid.

In the preferred form of the present invention as above set forth and as illustrated in the drawings, there are thirty-six horses comprised in the six columns and circles of the same, and in reality the thirty-six horses comprise six horses systematically arranged or placed so that each of the six is shown but once in the same row and but once in the same circle, such arrangement requiring that each horse shall be at the top of one column, second in another column, and so on to the bottom of a column, and provides an arrangement by which a player using any one column has an equal chance with the players using the other columns of the system. The numerals employed are for a more ready determination of the horses as the game progresses and the casting die is repeatedly thrown.

In playing the game, suitable rules are to be established for governing the players and the scoring of the points in the game, an example of such rules, and one affording a very entertaining contest is as follows:— With two players engaged in the game, each player will take three radial rows or columns of the figures, while with three players engaged in the game, each player will take two of said rows or columns, and a like equal division will be made with an increased number of players, and in some cases such equal division will be attained by the non-use of one or more of the rows or columns. With the desired allotment or selection made, one of the players takes and shakes and casts the die from the die-box upon the game board, and assuming for

- example that the throw is a six spot, the player that has the No. 6 horse on the top of his row is entitled to score three points; the player that has a No. 6 horse second from the top of his row is entitled to score two points, and the player that has a No. 6 horse third from the top of his row is entitled to score one point, with no other rows entitled to any score.
- 10 Fifteen points is the game, the lowest score losing the game, and should the last two or three players be entitled to a total score of fifteen on the last cast, the player which scores last loses. For instance, one player has three points to go, another has two points to go, while another has one point to go. The cast of the die shows a four spot. The first mentioned player has a No. 4 horse at the top of his row and is entitled to score three points and accordingly goes out. The next mentioned player has a No. 4 horse second from the top of his row and is entitled to score two points and also goes out. The last mentioned

player has a No. 4 horse third from the top 25 of his row, and being the last entitled to score loses the game. It is preferable that the same player, casts the die until the game is out, then the next player casts the die for the next game, and so on around the 30 board.

Having thus fully described my said invention what I claim as new and desire to secure by Letters Patent, is:—

A game board adapted for use in connection with a cubical casting die, and provided with a center field, and radial rows of figures, each row comprising a series of the same figures arranged so that the same figure will occur but once in a path concentric with the center of the field. 35 40

Signed at Chicago, Illinois this 28th day of June 1910.
